UNITED STATES PATENT OFFICE.

HENRY W. PLEISTER, OF WESTFIELD, NEW JERSEY, ASSIGNOR TO HENRY B. NEWHALL, FORMERLY KNOWN AS HENRY B. NEWHALL, JR.

BOLT ANCHOR.

Application filed April 12, 1922. Serial No. 552,050.

To all whom it may concern:

Be it known that I, HENRY W. PLEISTER, a citizen of the United States, residing at Westfield, in the county of Union and State 5 of New Jersey, have made certain new and useful Improvements in Bolt Anchors, of which the following is a specification taken in connection with the accompanying drawings.

10 My invention relates to a bolt anchor and more particularly to the shield and means to connect the portions of the shield together so that they will not become sprung or separated in handling, or storage or transportation.

15 My invention further relates to the combination of such a shield with an expanding member, which member is held within the shield by friction so that it will not become disconnected from the shield in such handling, storage and transportation.

20 My invention further relates to a shield which has separate cooperating interlocking breakable engaging members which have sufficient strength to hold the parts of the shield and the interposed expanding member together. The interlocking members, however, are not strong enough to interfere with the expansion of the shield when it is 25 expanded within a wall or other suitable support. Preferably the interlocking engaging members are undercut or dovetailed members, though of course this may be varied without departing from my invention.

30 My invention further relates to such a bolt anchor in which the shield and cone, or expanding member, are formed of materials of different strength, the expanding cone being of greater hardness and less ductility than the shield.

35 My invention further relates to forming the shield of some ductile material, as aluminum, brass, fibre lead or an alloy, so that when it is expanded the metal will flow, more or less, into the irregularities and voids of the wall of the hole. The expanding cone is formed of some harder material, as for example, iron, which may or may not 40 be galvanized.

45 My invention further relates to certain combinations, details of constructions, and articles of manufacture, which will be more fully hereinafter described and pointed out 50 in the claims.

In the accompanying drawings the same reference numerals refer to similar parts in the several figures.

Fig. 1 is a vertical section through a wall or other suitable support and the work supported, showing one form of my bolt anchor about to be expanded;

Fig. 2 is a vertical section, the same as Fig. 1, showing the bolt anchor expanded within the hole;

Fig. 3 is a side elevation of one form of my shield;

Fig. 4 is an end view of the shield shown in Fig. 3;

Fig. 5 is a detail vertical section of my expanding member shown in the form of a cone;

Fig. 6 is an end elevation of the cone shown in Fig. 5;

Fig. 7 is a side elevation showing the manner of assembling the shield and expanding member for shipment;

Fig. 8 is a cross section on the line 8—8 of Fig. 3;

Fig. 9 is a side elevation of a modification showing a different form of undercut or dovetail interlocking member;

Fig. 10 is a side elevation, similar to Fig. 9, showing the shield assembled with its cone ready for shipment;

Fig. 11 is a side elevation of the same shield, as shown in Fig. 3, with a wedge as the expanding member;

Fig. 12 is an end elevation of the assembled bolt anchor of Fig. 1;

Fig. 13 is a vertical section showing a modification wherein the expanding member is a lag screw which contacts directly with the shield;

Fig. 14 is a vertical section of a further modification in which the expanding member is a machine bolt which contacts directly with the shield;

Fig. 15 is a further modification in which the wood screw cuts its own threads within the ductile shield;

Fig. 16 is a cross section on the line 16—16 of Fig. 15;

Fig. 17 is a further modification showing the shield formed of separate parts connected together by the interlocking bendable or breakable engaging members;

Prior to my invention, it has been old to use an expansion shield formed of a plurality of parts and conical nuts, provided

with lugs or projections to cooperate with special engaging surfaces on the shield. To assemble these parts for shipping, it is necessary to bring the lugs or projections upon 5 the cone member into cooperating position with the special engaging surfaces on the shield, and then secure the parts together by some binding member, as for example, wire wrapped on the exterior of the shield, or 10 spring rings. This method is very expensive and unsatisfactory, for considerable time is taken in assembling each of the bolt anchors.

It is found in practice that the vibration, 15 jostling in transportation, and handling will cause many of the constituent parts of the bolt anchors to become separated, so that the dealer, before putting them upon his shelves, has to go over the shipment to see 20 whether or not all the bolt anchors are properly assembled and held together, and to reassemble such as have become separated during transit. This takes additional time, adds to the expense and is a considerable 25 annoyance to the dealer.

Prior to my invention it was also old to use cone nuts with tubular ductile lead sleeves having a tapered interior bore and walls of uniform circumferential thickness, 30 without grooves or slots to facilitate or even to permit expansion by means of a bolt and wrench.

Such expansions as I have just described required the use of special tools to drive 35 the lead shield down over the cone nut. They required the heavy blows of a hammer to caulk them down over the cone nuts to drift them out or expand them.

By means of slots extending into the axial 40 bore and one or more separate sets of interlocking breakable engaging members as hereinafter described, I overcome the disadvantages of the shield made of a plurality of parts provided with lugs, springs, etc., 45 and also overcome the objectionable features of the lead sleeves which required caulking tools and the laborious work of caulking them in the wall with a hammer.

By my invention I obtain a bolt anchor, 50 which can be manufactured at minimum expense; requires no additional member to secure the parts together; can be assembled with great speed and accuracy, and after being once assembled, the parts stay assembled and will not become disconnected during transportation or handling, so that all the annoyances and expense incident to the manufacture and sale of the present bolt anchors are avoided.

60 In my bolt anchor the shield may either have an integral body member and integral tines, or it may be formed of separate members connected together by sets of interlocking breakable or breakable engaging members. I have shown in Figs. 1 to 8, inclu-

sive, my shield 1 formed at one end with an integral body member 2 which is not slotted. This shield is provided with an axial bore 3 which has the tapered or flaring portion 4 extending from the end 5 towards the 70 body member 2, as shown in dotted lines in Figs. 1, 2, 3 and 7. In the particular form shown I employ two tines 6 and 7, which are integrally connected with the body member 2. They are also connected at 75 their other ends by one or more separate sets of interlocking bendable or breakable engaging members. These members are sufficiently strong to prevent the tines being spread apart in handling or transportation and are also sufficiently strong to withstand the wedging action of the cone 8, when it is driven in lightly into the flaring axial bore 4 as shown in Fig. 7. This is to insure that after the cone 8 has once been assembled by being driven into the axial bore as 80 shown in Fig. 7, it will be held by friction. It will not drop out of the shield from vibrations in transportation, or from rough handling, thereby obviating the necessity of the purchaser or jobber going over the shipment to see whether or not all the bolt anchors are properly assembled and held together, and to reassemble such as have become separated during transmission.

The particular form of separate interlocking bendable or breakable engaging members between the tines 6 and 7 may vary as found convenient or expedient. In casting the shield 1, I cast the slots 9, 9 so that they extend from the exterior surface of the shield into the axial bore 4, as shown in Fig. 8. At the same time I cast the interlocking bendable or breakable engaging members 10 and 11, one of them being upon 100 one of the tines and the other cooperating locking member upon the other tine. Preferably these cooperating members are formed as undercut or dovetail engaging members, as shown in Figs. 1, 2, 3 and 7.

In positioning the complete assembled bolt anchor, Fig. 7, it is inserted into the hole 12 in the wall or other suitable support 13 until the surface 14 of the shield is brought flush with the surface of the wall 115 13. The machine or other bolt 15 is then inserted through a hole in the work 16 until its screw threads cooperate with the threads 17 in the cone 8, as shown in Fig. 1. By then rotating the head of the machine bolt 120 15, the cone 8 is caused to move up the inclined or flared axial bore 4 towards the work 16, but in doing so it will ordinarily fracture or rupture the cooperating interlocking, bendable or breakable engaging members 10 and 11. The parts will then 125 be in the position shown in Fig. 2.

In some instances if the hole 12 is accurately drilled in the wall and there is a close fit between the shield 1 and the wall 130

of the hole, the cooperating engaging members 10 and 11 might simply stretch without breaking. Ordinarily however, the cooperating engaging surfaces would be ruptured or 5 broken as shown in Fig. 2.

If the shield 1 is formed of some ductile material, as in the preferred construction, the metal of the shield will be caused to flow, more or less, into the interstices found 10 in the wall surrounding the hole. Such interstices are formed in the wall of holes drilled in manufactured stone or brick, and in natural stone, by the dislodgement of pebbles, coarse sand, and hard particles constituting the mass. By forcing the metal 15 to flow in these inequalities I obtain a particularly strong union or hold with the wall or other suitable support.

Used in an accurately drilled hole the 20 ductile shield is compressed or shortened between the nut and the work and at the same time the diameter of the shield is increased uniformly in all directions limited only by its powerful contact with the contour of the 25 hole.

In Figs. 9 and 10, I have shown a modification of my invention in which the shield 30 18 is provided with the same tines 6 and 7 separated by the slot 9. In this as in the other form my interlocking bendable or breakable engaging members 19 and 20 are undercut, and might be called half a dovetail. In Fig. 10, I have shown the position 35 of these undercut members 19 and 20 when the conical nut 8 is assembled ready for shipment.

I have shown a modification of my invention in Figs. 11 and 12 in which the shield 1 is the same as that shown in Figs. 40 1, 2, 3 and 7, but instead of using a conical nut 8, I use a wedge 21.

My invention is not to be confined simply to a shield which is expanded by a cone, wedge or other similar expanding member. 45 I may, for example, form a shield 22 as in Fig. 13 having a body member 23 and tines 24 and 25 connected together by the same interlocking bendable or breakable engaging members 10 and 11. In this form 50 the expansion is caused by the lag screw 26 cooperating directly with the screw threads 27 within the tines 24 and 25, and without the aid of a cone or wedge.

In Fig. 14 I have shown a further modification in which the machine bolt 28 cooperates with the machine threads 29 within the shield 30 to expand the tines 31 and 32.

In some cases the screw, as for example 60 the wood screw 33, is screwed within the ductile shield 34 cutting its own screw threads and at the same time expanding the tines 35 and 36, which are connected at one end by the body member 37, and at their other end by the interlocking bendable or breakable engaging members 10 and 11.

In some cases I may form a shield of a plurality of separate elements as shown in Fig. 17. In this modification, the shield 38 is formed of the separate and distinct members 39 and 40 which are not connected together except by separate sets of interlocking bendable or breakable engaging members 10 and 11. 70

Having thus described this invention in connection with illustrative embodiments 75 thereof, to the details of which I do not desire to be limited, what is claimed as new and what is desired to secure by Letters Patent is set forth in the appended claims. 80

What I claim is:—

1. A new article of manufacture comprising a shield having an integral body member and a plurality of tines extending from said body member, said tines having one or more sets of interlocking bendable or breakable engaging members adapted to hold the tines together and also hold an interposed expanding member, for handling, storage and transportation and an interposed expanding member. 85

2. A new article of manufacture comprising a shield having one or more sets of independent separated interlocking bendable or breakable engaging members, adapted to hold the parts of the shield together and also to hold an interposed expanding member from becoming disconnected from the shield in handling, storage and transportation and an interposed expanding member. 95

3. A new article of manufacture comprising a shield having a body member and a plurality of tines said tines being connected together by undercut or dovetail engaging members. 100

4. An assembled bolt anchor comprising a shield having one or more sets of separated interlocking bendable or breakable engaging members, and an expanding member pressed into said shield to cause the interlocking engaging surfaces to cooperate and hold said expanding member by friction without breaking the engaging members, so that the parts of the assembled bolt anchor will not become separated in handling, storage and transportation. 110

5. An assembled bolt anchor comprising a shield having a body member and a plurality of tines, said tines being connected together by cooperating interlocking members and an expanding member pressed between the tines to cause the cooperating interlocking members to engage with each other and hold the expanding member by friction so that the parts of the assembled bolt anchor will not become separated in handling, storage and transportation. 120

6. An assembled bolt anchor comprising a shield having a body member and a plurality of tines, said tines being connected 125

1 together by cooperating dovetail or undercut members and an expanding member pressed between the tines to cause the dovetail or undercut members to engage with each other and hold the expanding member by friction so that the parts of the assembled bolt anchor will not become separated in handling, storage and transportation.

7. An assembled bolt anchor comprising 10 an expansible ductile shield having an integral body member and integral ductile tines, the free ends of said tines being connected together with separated interlocking

members, and an expanding member pressed between said tines and held by frictional engagement therewith, said separated interlocking members being of sufficient strength to hold the tines from expanding in handling, storage and transportation, and adapted to be bent or broken when the shield is expanded into its operative position. 15 20
